(57) CLAIM

The ornamental design for a tub, as shown and described.

DESCRIPTION

FIG. 1 is a perspective view taken from the top, front, and right side of a tub for bathing showing my new design;

FIG. 2 is a side view thereof, the opposite side being identical thereto;

FIG. 3 is a top plan view of a bathtub showing my new design; and,

FIG. 4 is a side view thereof; the opposite side being identical thereto.

Shading and broken lines are for illustrative purposes only and form no part of the claimed design.
